INVENTOR
Eric A. Wolfram.

UNITED STATES PATENT OFFICE

ERIC A. WOLFRAM, OF ROCK ISLAND, ILLINOIS

DRAFTING TOOL

Application filed January 19, 1931. Serial No. 509,845.

My invention has reference to a drafting tool, and more specially to a radial rule, embracing a rule or straight-edge, and supporting arms therefor capable of a compound movement, making it possible to effect endless variations in the position of the rule, for making lay-outs of gear-teeth, ratchet-wheels, generators, rotary cutters, and other figures involving a repeated drawing of tangent lines, radial lines, and lines taking off from radial lines.

The invention is designed for operation on a drawing board or other plane surface, and the support for the rule consists of a compound arm one end of which is fitted with a needle-point for insertion in the drawing board, and the other end of which has a pivotal connection with the rule. The needle point forms a pivot about which the instrument may be turned for a complete revolution. Clamping devices are also provided for holding the rule or supporting arms in adjusted positions. Adaptations are also possible wherein one or both of the arm members can be omitted, the pivoting element being connected directly with the remaining arm or with the rule itself.

The construction, arrangement, and manner of using the invention will be more fully understood from the following specification, reference being had to the accompanying drawing, in which;—

Fig. 1 is a plan view of the invention.

Fig. 2 is an edge view thereof.

Fig. 3 is a cross-section on the broken line 3—3 of Fig. 1.

Fig. 4 is a fragmentary detail showing a different arrangement of the tool, as applied to the arm 2.

Fig. 5 is a similar showing of a varied arrangement for the rule 1.

The reference number 1 indicates a linear rule, preferably formed of a strip of sheet metal, the sides of which are parallel straight edges. An arm 2 has a pivotal connection with the rule, at a point between its ends, by means of a bolt 3, passing through said parts, and threaded at its end to receive a thumb-turn 4, by means of which the rule and arm

2 may be clamped together for unitary action.

The other end of the arm 2 is pivotally connected with a shorter arm 5, by means of a bolt 6, provided with a thumb-turn 7, by tightening which the arms 2 and 5 may be held from movement independently of each other. If desired, washers may be used between the arms 2 and 5, and between the other end of the arm 2 and adjacent parts, as shown at 9 and 10. The arm 5 has an upwardly bent extension 11, in which is held an eyebolt 12, provided on its threaded end with a thumb-nut 13. Slidable in the eye of the bolt 12 is a needle-pin 14, which can be held from movement by tightening the nut 13. The relative lengths of the arms 2 and 5 may be varied in any desired manner.

When in use the rule 1 is laid upon the paper on a drawing board, and a connection made between the tool and board by means of the pin 14. One end of the rule is then positioned to conform to the radial line or other line which is to be reproduced, and the nuts 4 and 7 tightened to hold said parts in an established position. One or other of the straight-edges of the rule can then be used as a guide for the pencil in forming the desired lines. After one line has been produced by the use of the rule any desired number of movements thereof can be made about the pin 14 as a center to effect a repetition of said lines. The point at which said pin is set is the center of the circumference of the object which is being laid out, and by movement of the rule one side of a gear tooth, or ratchet tooth, or other figures can be repeated any desired number of times.

It will be obvious that the arm 2 can be turned for operation on either side of the arm 5, and either edge of the tool can be used in forming the lines. At A in Fig. 1 is indicated a fractional part of a lay-out of ratchet teeth, the rule being in position for forming the radial edges of the teeth, and by rotating said rule for predetermined intervals about the pin 14, all of the radial edges can be outlined. By positioning the tool as shown in broken lines the sloping edges of the teeth can be indicated on the drawing. In this work

the tool can be guided by one hand and the pencil made use of by the other one. The rule 1 can also be provided with a scale, as indicated at 15. The arms 2 and 5 can also 5 be integrally formed, where the adjustment of the rule 1 alone is required. When the arms are pivotally connected an adjustment thereof may be made to space the pivot point of the rule a greater or less distance from the 10 center-point, to accommodate such rule to the work.

For some kinds of work the arm 5 can be dispensed with, and one end of the arm 2 provided with an upward extension 16, (Fig. 4) 15 in which is held an eye-bolt 17, in which is held a needle-pin 18, the bolt being fitted with a thumb-turn 19. The rule is pivoted to the other end of the arm 2 as in the former showing, the pivotal point being rotatable 20 about the pin 18, and the rule pivotally adjustable as before. In Fig. 5 is indicated a form wherein both of the supporting arms are omitted, one end of the rule 1 being turned upwardly at 20, for the support of an eye-bolt 21, in which is held a pin 22, by means of 25 a thumb-nut 23. In this form the rule can be rotated about the pin 22, in the formation of some simple figures. In all of the forms shown the needle-pin can be adjusted vertically by loosening the nut on the eye-bolt.

What I claim, and desire to secure by Letters Patent, is:

1. A drafting tool, comprising a linear rule, a compound arm support therefor provided 35 at one end with a needle-point for insertable engagement with a drawing-board, and about which said arm may rotate freely and pivotally connected with the rule at the other end, and means for holding said rule immovable 40 with relation to said support.

2. A drafting tool, comprising a primary arm provided at one of its ends with a needle point for pivotal attachment to a plane surface, a secondary arm pivoted to said primary arm, means for holding said arms from relative movement, a linear rule pivoted to said secondary arm, and means for holding said last-named arm and rule from relative movement, said rule being supported so as to be 45 slidable on said plane surface.

3. A drafting tool, comprising a support formed of angularly disposed arms, a needle point connection at one of the ends of said support, and a linear rule having a pivotal 55 connection with the other end thereof, at a point intermediate the ends of said rule and adapted for a slidable movement on the face of a drawing board.

4. In a drafting tool, a primary arm bent 60 upwardly at one end to form a vertical support for a needle-point, a needle-point connected with said support and adapted for a penetrable attachment to a plane surface, with said arm in slidable relation with said plane surface, a secondary arm pivotally connected 65

with said primary arm, and a linear rule having a pivotal connection with said secondary arm, also arranged for a slidable contact with said plane surface.

5. In a drafting tool, a primary arm 70 adapted for a slidable engagement with a plane surface, and provided at one of its ends with a needle-point support, a needle-point held in said support vertically to the plane of said arm, and capable of adjustment vertically, a secondary arm pivoted to the other end of said primary arm, a linear rule having a pivotal connection with said secondary arm, and adapted for a slidable contact with said plane surface, and means for holding said rule in fixed relation with said needle-point.

In testimony whereof I affix my signature.

ERIC A. WOLFRAM.
